MULTIPLE TOTALIZER SELECTING MEANS

Hubert Neureiter, Essen, and Albert Klaar, Bielefeld, Germany, assignors to The National Cash Register Company, Dayton, Ohio, a corporation of Maryland

Application July 29, 1937, Serial No. 156,324
In Germany July 21, 1932

14 Claims.

(Cl. 235—6)

The present invention relates to cash registers and accounting machines, and concerns more particularly the totalizer selecting mechanism and the tens carrying mechanism.

5 It is old and well known in the art to select for simultaneous operation a plurality of totalizers each of which is arranged on a different shaft. However, it is often desirable to select for simultaneous operation a plurality of totalizers all arranged on a common shaft. To this end the present invention provides novel means for selecting a variable number of totalizers arranged on a common shaft, together with special tens carrying mechanism for performing the 10 proper transfer from lower to higher denominational order wheels.

It is, therefore, a primary object of this invention to provide novel means for selecting for operation a plurality of totalizers all arranged on a 15 common shaft.

Another object is to provide means for selecting a variable number of totalizers all arranged on a common shaft.

20 A further object is to provide means for causing a plurality of totalizers, arranged in interspersed fashion on a common shaft, to be actuated by a single differentially movable actuator.

An additional object is to provide means whereby a variable number of totalizers, all arranged 25 on a common shaft, may be selectively coupled to a single differentially movable actuator.

Another object is to provide means for transferring a total from one of a plurality of totalizers mounted on a common shaft to any other 30 one of said totalizers.

A still further object is to provide novel tens carrying mechanism for transferring from a lower denominational wheel to a higher denominational wheel.

35 With these and incidental objects in view, the invention includes certain novel features of construction and combinations of parts, the essential elements of which are set forth in appended claims and a preferred form or embodiment of 40 which is hereinafter described with reference to the drawings which accompany and form a part of this specification.

Of said drawings:

Fig. 1 is a side view of the bank of totalizer 45 selecting keys, showing the means by which the lower group of said keys controls the adjustment of the differential mechanism associated therewith, and the totalizer selecting lever.

Fig. 2 is a side view of the means by which 50 the upper group of said totalizer selecting keys

controls the adjustment of the differential mechanism associated therewith.

Fig. 8 is a sectional view along lines VIII—VIII 15 of Fig. 10, through the device for shifting the tens carrying means.

Fig. 9 is a side view of a denominational group of totalizer wheels in engagement with their differential actuator, after having tripped the tens carrying mechanism therefor.

Fig. 10 is a side view of one of the denominational groups of totalizer wheels and the tens carrying mechanism therefor, the latter being shown in its normal position.

Fig. 11 is a side view of another one of the 25 groups of denominational totalizer wheels and the tens carrying mechanism associated therewith, the latter being in its normal position.

Fig. 12 is a detail side view taken on line XII—XII of Fig. 6, looking toward the left, showing 30 a portion of the driving means for the differential mechanism.

Fig. 13 shows the same as Fig. 10, only after the tens carrying mechanism has effected a carry.

Fig. 14 is a side view of the totalizer selecting 35 lever and the operation control lever.

Fig. 15 is a top plan view of the restoring mechanism for the totalizer selecting lever.

Fig. 16 is a side view of a modified form of 40 totalizer selecting means with the tens carrying mechanism therefor.

Fig. 17 is a sectional view taken along lines XVII—XVII of Fig. 16, through a row of totalizers, showing the coupling means of the modified embodiment.

Fig. 18 is a time chart indicating the time of 45 operation of the various parts of the machine.

DETAILED DESCRIPTION

The machine herein illustrated is provided 50 with a plurality of totalizers similar to the totalizers shown and described in United States Letters Patent to Lehmann et al., 2,108,896. Each totalizer comprises adding wheels 10 (Fig. 7) arranged in interspersed order on a common shaft or 55

support. For instance, the adding wheels of the same denomination for each totalizer are grouped together, there being a group of "units" adding wheels, a group of "tens" adding wheels, and so on. Each denominational group of adding wheels 10 is freely mounted on a hub 11 of a setting wheel 12 corresponding to that particular group of wheels. The setting wheels 12, in turn, are freely mounted on a sleeve 14 which is nested 10 on a sleeve 21 shiftably mounted on a rod 20 (Figs. 7 and 10). Each setting wheel 12 is associated with and adapted to be actuated by an individual differentially movable actuator 13. During each 15 operation of the machine, the actuators 13 are rocked first clockwise and then counterclockwise, under control of banks of amount keys, as clearly shown in the above Patent No. 2,103,896, and thus rotate the setting wheels 12 extents commensurate with the value of the amount keys depressed.

The ends of the hubs 11 contact each other, and the wheels 12 are mounted in hubs in the upper ends of totalizer carriers 16 secured to a shaft 19. The latter is connected, in any desired manner, 25 with the machine drive and is rocked thereby at different times (Fig. 18) to either engage the setting wheels 12 with the actuators 13 in the performance of an adding operation or engage the adding wheels 10 with toothed sectors 115 30 and 127 (Figs. 9, 10, 11 and 13) to transfer "one" from a wheel 10 of lower order to a wheel 10 of next higher order. When the machine is at rest, the shaft 19 is positioned to hold the totalizer wheels in an ineffective position, as shown in Fig. 35 10. The adding wheels 10 are prevented from being accidentally moved out of their respective positions during the above mentioned rocking movements of the shaft 19 by means of spring-pressed retaining pawls 135 mounted on a rod 136 40 supported by the totalizer carriers 16. The time of the engaging and disengaging movements of the totalizer wheels is shown in the time chart, Fig. 18.

Means is provided for selectively coupling one 45 or more adding wheels 10 of each denominational group to the setting wheel 12 associated therewith, so that said selecting adding wheels 10 will be actuated the same extent as imparted to the wheel 12 by differentially movable actuator 13. This means will now be described.

Each sleeve 14 (Fig. 7) comprises a plurality of 50 individual sections all located end to end on the sleeve 21 carried by the shaft 20. Each sectional sleeve 14 is associated with a different denominational group of adding wheels 10. The various sections of the sleeve 14 are free to rotate independently of each other about the sleeve 21 but are compelled, by means of a plate 17 secured at one end of the shaft 20 and a pin 18 (Fig. 5) extending through the opposite end of said shaft, to 55 take part in any shifting movement imparted to the shaft 20. When participating in such shifting movement, the various sections comprising the sleeve 14 move in unison as one single body. The sleeve 21 is provided with an elongated slot 22 through which extends the pin 18, thus permitting the shaft 20 and the sleeve 21 to be shifted relatively to each other.

Associated with each denominational group of 70 adding wheels 10 is a coupling member 15 (Figs. 7 and 10) rotatably mounted in an annular groove formed in the section of the sleeve 14 corresponding to that particular group of adding wheels. The member 15 protrudes through a transverse 75 slot formed in the hub 11 of the setting wheel 12.

The member 15 is shiftable with the sleeve 14 to engage internal teeth 24, of any one of the adding wheels 10 associated therewith, from the ninth down to the second totalizer, to thereby couple said adding wheel to the common setting wheel 12 therefor. The member 15, when in its normal extreme left hand position (Fig. 7), enters an internal groove 23 of its respective totalizer carrier 16 whereby the member 15 is prevented from being shifted unintentionally. However, 10 before the sleeve 14 is rotated for any operation, the member 15 may be shifted to the right to select a totalizer for actuation. When the shaft 20 and the sleeve 14 are shifted to the right by means to be hereinafter described, the members 15 are simultaneously moved into engagement with the internal teeth 24 of the adding wheels 10 of one of the totalizers, so that the adding wheels of the totalizer selected are coupled to the associated setting wheels 12.

Likewise, associated with each denominational group of adding wheels 10 is another coupling member 25 rotatably mounted in an annular groove formed in the sleeve 21. The member 25 also protrudes through the transverse slot in the hub 11 of the setting wheel 12. Like the member 15, the member 25 is shiftable with the sleeve 21 to engage internal teeth 24 of any one of the adding wheels 10 associated therewith, from the first totalizer to and including the ninth totalizer, 30 to thereby couple said adding wheel 10 to the common setting wheel 12 corresponding thereto. The member 25, when in its normal extreme right hand position (Fig. 7), engages internal teeth of its respective setting wheel 12 and is thus prevented from engaging the internal teeth 24 of any of the adding wheels 10. When in this position the member 25 will rotate idly with the setting wheel 12. Thus, when the sleeve 21 is shifted to the left by means to be hereinafter described, the members 25 are simultaneously moved into engagement with the internal teeth 24 of the adding wheels 10 of one of the totalizers, so that the adding wheels of the totalizer selected are coupled to their associated setting wheels 12.

Thus, from the above it will be seen that when the actuators 13 actuate their respective setting wheels 12, the members 15 and 25 associated with each of said setting wheels are, by means of the hub 11, caused to be rotated with their respective setting wheel 12. The lateral shifting of the members 15 and the members 25 relatively to each other determines which totalizers are to be coupled to the setting wheels 12 during an operation of the machine.

The means for shifting the members 15 in the manner above described will now be explained. The right hand end of the sleeve 14 (Fig. 5) is adapted to be rocked within a slot 26 (Fig. 3) of a plate 27 but is incapable of being shifted transversely in said slot. The plate 27, in turn, is shiftably mounted on two rods 28 and 29 and has a guide roller 30 engaging a cam groove 31a formed in a drum 31. While the sleeve 14 is not shiftable in the slot 26 it is shiftable with the plate 27, as will be more fully described hereinafter. The drum 31 is secured to a shaft 32 (Figs. 3 and 5) suitably journaled in side frames of the machine. Fast to the right hand end of the shaft 32 is a gear 33 meshing with a setting segment 34 secured to a shaft 35 which has fast thereto an arm 142 (Figs. 6 and 12). The free end of the arm 142 is notched to contact a stud 143 of an arm 144, secured to the hub of a gear 145. A spring 41, attached to segment 34, main-

tains the notch of arm 144 in contact with the stud 143. The gear 145 meshes with a segment 179 secured to shaft 178a. The shaft 178a is rocked during each machine operation, by any suitable means connected to a main shaft, to oscillate the gear 145 and arm 144 in the manner hereinafter described. With the gear 145 in its home position, as shown in Fig. 12, the arm 144, segment 34 and drum 31 are so positioned that the cam groove 31a formed in the latter will position the plate 21 so that the shaft 20, sleeve 14 and members 15 are in their extreme left hand positions, with the members 15 rendered ineffective because at this time they are in engagement with the internal gear 23 (Fig. 7) of their respective totalizer carriers 16.

As shown in the time chart, Fig. 18, after the amount differential actuators 13 are adjusted, the arm 144, through the gear 145, is given an oscillatory movement, first in a clockwise direction (Fig. 12) until the pin 143 thereof assumes a position designated by 143', and then, after the actuators 13 are returned to their home positions, the arm 144 is returned in a counter-clockwise direction to its home position. When the arm 144 is rocked clockwise as just described, a spring 41 (Fig. 3) tends to rock the segment 34 in a like direction but is prevented from doing so by a pin 36 thereon contacting the lower end of a slot 37 formed in a setting segment 38 freely mounted on the shaft 35. The segment 38 serves to adjust the tens carrying mechanism which will be hereinafter described. A spring 39 normally causes the segment 38 to contact a pin 40a of an arm 40 (Fig. 6) joined by means of a sleeve to a gear 140 connected to an intermittent oscillatory drive of the well-known type. When the machine is at rest, the pin 36 coacts with the lower end of the slot 37 in the segment 38 (Fig. 3).

During an operation of the machine after the amount differentials have been adjusted, the arm 40 is rocked clockwise in substantially the same manner as the arm 144 until the pin 40a assumes the position designated by 40a' (Fig. 3), from which position it is not returned to its home position until at the end of the operation. During the clockwise movement of the arm 40, the segment 38, under the action of the spring 39, is likewise moved in a clockwise direction. This clears the path of the pin 36 so that the segment 34, under the action of the spring 41, is moved in a clockwise direction to follow the arm 144 during the latter's clockwise movement. When this occurs, the segment 34, meshing with the gear 33, rotates the shaft 22 and drum 31 counter-clockwise (Fig. 3). Due to the shape of the cam groove 31a, the drum 31 will at this time shift the plate 21, shaft 20 and sleeve 14 to the right and thus engage the members 15 with the internal teeth 24 of the adding wheels 10. When this is accomplished, the adding wheels of the selected totalizer are coupled to their respective setting wheels 12. The means for controlling the selection of the different totalizers will be hereinafter described.

After the amounts have been added into the totalizer, the arm 144 is rocked counter-clockwise to its home position (Fig. 12) and in so doing the pin 143 coacts with the arm 142 to return the segment 34, the gear 33, drum 31, plate 21, sleeve 22, shaft 20 and members 15 to their home positions. Since the arm 40 is not rocked counter-clockwise to its home position until later, i. e., at the end of the operation, the segment 38 re-

mains stationary for awhile, the slot 37 permitting the segment 34 to return counter-clockwise to its home position.

The means for shifting the members 25 in the manner hereinbefore described will now be explained. The right-hand end of the sleeve 21 (Figs. 4 and 5) projects through a slot formed in a plate 42 shiftably mounted on the rods 28 and 29. The sleeve 21 is rockable within the slot in the plate 42 but is shiftable only with the plate 42. The plate 42 is provided with a roller 43 which engages a cam groove 44a formed in a drum 44 rotatably mounted on a sleeve 44' loose on the shaft 32.

Rigidly mounted in the hub of the drum 44 is a stud 156 (Fig. 5) having pivoted thereon a beveled pinion 151. The pinion 151 meshes with a pair of beveled gears 152 and 153. The gear 152 is fast to a gear 154 secured to the left end of a sleeve 154' loose on the hub of the drum 44, while the gear 153 is secured to the left end of the sleeve 44'. The gear 154 meshes with a gear 155a which, in turn, meshes with a toothed segment 155b loosely mounted on a sleeve 155' on the shaft 35. The segment 155a, through the gears 155b and 155c, both secured to a shaft 45, is constantly connected to a toothed segment 156 of a totalizer selecting lever 157 (Fig. 14) on the shaft 35.

The beveled gear 153 is connected, by means of the sleeve 44' (Fig. 5), to a gear 45 constantly meshing with a setting segment 46 (Fig. 4) pivoted on the shaft 35. The segment 46 is connected by means of the sleeve 155' to an arm 146. A spring 52 connected to the segment 46 normally holds the arm 146 (Figs. 6 and 12) in contact with a pin 147 of an arm 148 which is connected, through a gear 149, to an intermittent oscillatory drive mechanism.

With the arm 146 in its home position, as shown in Fig. 12, the segment 46 will position the drum 44 so that the cam groove 44a formed therein will hold the plate 42 and sleeve 21 in their extreme right hand position, thus placing the members 25 in their normal ineffective positions.

After the amount differential actuators 13 are adjusted, the arm 148 is rocked counter-clockwise (Fig. 12) until the pin 147 assumes the position designated by 147', and the arm 148 is not returned clockwise to its home position until after the actuators 13 are restored to their initial positions. During the counter-clockwise movement of the arm 148, the segment 46, under the action of a spring 52 (Fig. 4) tends to follow the arm 148 in its counter-clockwise movement. However, such counter-clockwise movement of the segment 46 is prevented by a pin 47 thereon contacting the upper end of a slot 48 formed in an adjusting segment 49 loosely mounted on the sleeve connecting the arm 40 with the gear 140 (Fig. 6). The segment 49 serves to set the proper tens carrying mechanism, as will be hereinafter described. A spring 53 normally tends to hold the segment 49 in contact with a pin 51a of an arm 51 (Figs. 4 and 6). The arm 51 is connected, by a sleeve, to a gear 141 freely mounted on the shaft 35, and the gear 141 is connected to an intermittent oscillatory drive mechanism (not shown). The segment 49 is shown in its home position in Fig. 4. Before the adjustment of the amount differential actuators 13 takes place, the oscillatory drive mechanism just referred to rocks the arm 51 in a counter-clockwise direction until the pin 51a assumes the position designated by 75

51a' (Fig. 4). The arm 51 is not returned to its home position until at the end of the operation. When the arm 51 moves counter-clockwise, the spring 50 moves the segment 49 so that the pin 47 is free to move upwardly in slot 48, and the spring 52 rocks the segment 46 counter-clockwise to follow the arm 148. When the segment 46 is thus rocked counter-clockwise it will, through the gears 45, 153, and 151, rotate the drum 44 an extent commensurate with the totalizer selecting key depressed. At such time, the gears 152 and 154 are held stationary by the totalizer selecting lever 151 to create a planetary gearing effect for the purpose of rotating the drum 44. The cam groove 44a is of such shape that when the drum 44 is rotated as just described it will shift the plate 42 and sleeve 21 toward the left to engage the members 25 with the internal teeth 24 of the adding wheels 10, thus coupling the adding wheels of the totalizer selected to their corresponding setting wheels 12.

After the amount differential actuators 13 are returned to their home positions, the arm 148 is restored to its initial position by the oscillatory drive mechanism previously referred to. During such clockwise movement, the arm 148 coacts with the pin 147 to return the arm 146 and segment 46 to their home positions. Such restoration of the segment 46 to its home position causes the drum 44 to be rotated to shift the plate 42 and sleeve 21 to the right to restore the members 25 to their extreme right hand ineffective positions.

35 Totalizer selecting mechanism

A bank of totalizer selecting keys 80 (Figs. 1 and 2) is provided for determining the extent of shifting movement imparted to the members 15 and 25 to selectively couple the adding wheels 10 of a plurality of totalizers to their respective common setting wheels 12.

Each arm of the setting segments 38 and 49 is provided with two stop faces 53, 54 and 55, 56, respectively (Fig. 1). With the machine at rest, the stop face 53 of the segment 38 contacts one end of a zero stop pawl 57 pivoted on a stud 58 of a totalizer key bank frame 58a. A spring 59 normally urges a pin 60 of the zero stop pawl 57 into contact with a projection 61 of a detent 62 carried by two arms 62a and 62b pivoted to the key bank frame 58a. The detent 62 is normally urged downwardly by a spring 63 until the arm 62a contacts stationary stud 64 carried by the frame 58a. With the zero stop pawl 57 in the position just described, the segment 38 is thereby held in its zero position against the action of the spring 39 (Fig. 3) when the rocking arm 40 is actuated. If, however, the zero stop pawl 57 is moved out of the path of the stop face 53, by depression of one of the totalizer selecting keys 80 as will be hereinafter described, the segment 38, under the action of the spring 39, is rocked clockwise to follow the arm 40 until its stop face 54 strikes the lower end of a depressed key 80. When this occurs, the arm 40 continues its invariable rocking movement until the pin 40a assumes the position designated by 40a', and when moved counter-clockwise to its home position restores the segment 38 to its normal position. During such clockwise movement of the segment 38, the drum 44 is rotated in the manner previously described to shift the shaft 20 and sleeve 14 toward the right an extent commensurate with the key 80 depressed, to engage the members 15 with the

adding wheels 10 of the totalizer corresponding to the depressed key 80.

If the zero stop pawl 57 is not moved out of its effective position by depression of one of the keys 80, the segment 38 is thus prevented from following the arm 40 in its clockwise movement. Since the pin 36 abuts against the lower end of the slot 37 (Fig. 3), the segment 34 is prevented from moving clockwise to follow the arm 144. Consequently, the shaft 20 and sleeve 15 associated therewith are not shifted to the left and the members 15 are not moved out of their normal ineffective positions.

With the machine at rest, the stop face 55 of the setting segment 49 contacts one end of a zero stop pawl 65 pivoted to the frame 58a. A spring 66 normally urges the pawl 65 counter-clockwise to cause a pin 67 thereon to abut against a projection 68 formed on a detent 69 (Fig. 2). The detent 69 is carried by a pair of arms 69a and 69b pivoted to the key frame 58a. The detent 69 is normally urged downwardly by a spring 70 to cause the arm 69a to abut against the pin 64. With the zero stop pawl 65 in the position just described, the setting segment 49 is thereby held in its zero position, against the action of the spring 50 (Fig. 3), while the arm 51 (Fig. 1) is rocked counter-clockwise during an operation of the machine.

Depression of any of the upper four totalizer selecting keys 80, through means to be later described, causes the zero stop pawl 65 to be rocked out of the path of the stop 55 on the setting segment 49. Thus the segment 49 will, under the action of the spring 50, follow the counter-clockwise movement of the arm 51 during an operation of the machine until the stop 55 on said segment strikes the end of the depressed key. This arrests the counter-clockwise movement of the segment 49 but the arm 51 continues its invariable counter-clockwise movement until the pin 51a reaches a position designated by 51a' (Fig. 1). Such counter-clockwise movement of the segment 49 clears the path of the stud 47, whereupon the spring 52 (Fig. 4) rocks the segment 46 counter-clockwise to rotate the drum 44 in the manner hereinbefore described. Such rotation of the drum 44 causes the shifting of the plate 42 and sleeve 21 toward the left a distance commensurate with the key 80 depressed. This causes the members 25 to engage the adding wheels 10 of the totalizer selected by the depressed key and thereby couple said wheels to their respective setting wheels 12, as previously explained.

Depression of any one of the lower five totalizer selecting keys 80 causes the zero stop pawl 57 to be rocked out of its normal effective position. The means actuated by said keys 80 for accomplishing this result will now be described.

The detent 62 has inclined surfaces 72 coacting with pins 73 on the five lower keys 80. Whenever one of the five lower keys 80 is depressed, the pin 73 will coact with one of the inclined surfaces 72 on the detent 62 and cam the latter upwardly against the action of a spring 63. During such upward movement, a projection 61 on the detent 62 will coact with the pin 60 and rock the zero stop pawl 57 clockwise, against the action of the spring 59, thus removing the right-hand end of said pawl (Fig. 1) out of the path of the stopping face 53 on the setting segment 38. This permits the segment 38 to be moved by spring 39 until arrested by the stem of a depressed key 80, as hereinbefore explained.

Tens carrying mechanism

Pivottally mounted on pins 76 carried by the detent 62 are five pawls 75 having inclined surfaces 75a. The pawls 75 are normally held against pins 78 of the detent 62 by springs 77, in which positions the upper edges of the pawls 75 are out of the path of movement of the pins 73 on the keys 80. When, upon depression of one of the five lower keys 80, the detent 62 has been moved upwardly, the pawls 75 are thereby rocked so that the inclined surfaces 75a thereof confront the key pins 73 of the four remaining undepressed lower keys 80. Thus, if one of the four undepressed lower keys 80 is depressed, the pin 73 thereon will coat with the inclined surface 75a of its respective pawl 75 and cam the detent upward an additional extent. The pawl 75 of the first depressed key 80 above mentioned is then able to diverge against the action of its spring 77, whereas an upper projection 74 on the detent 62 coats with a pin 67 on the zero stop pawl 65 and rocks the latter clockwise to remove the right-hand end thereof from the path of the stop face 55 on the segment 49.

Similar to the detent 62, the detent 69 (Fig. 2) has four inclined surfaces 79 thereon cooperating with the pins 73 of the four upper totalizer selecting keys 80. Depression of any one of said keys 80 causes the pin 73 to coat with one of the inclined surfaces 79 and cam the detent 69 upwardly against the action of a spring 70. During such upward movement of the detent 69 a projection 68 formed thereon coats with a pin 67 on the zero stop pawl 65 and rocks the latter clockwise out of the path of the stop face 55 on the setting segment 49. During such movement of the detent 69 another projection 82 thereon is moved into contact with the pin 60 on the zero stop pawl 57. Also pivotally mounted on pins 83 carried by the detent 69 are four pawls 84 having inclined surfaces 84a. Springs 85 normally hold the pawls 84 against pins 86 on the detent 69. If, after depressing one of the four upper keys 80 and thereby rocking the detent 69 upwardly to move the pawl 65 out of the path of the segment 49, another one of said upper keys 80 is depressed the pin 73 thereon will coat with the surface 84a of its respective pawl 84 and cam the detent 69 further upward. Such additional upward movement of the detent 69 causes the projection 82 to rock the zero stop pawl 57 out of the path of the stop face 54 on the setting segment 38.

From the foregoing description it will be understood that if no keys 80 are depressed, the setting segments 38 and 49 are retained in their zero positions by the zero stop pawls 57 and 65, respectively. If only one key 80 is depressed in either the upper group or lower group of keys, then either the setting segment 49 or the segment 38 is released for operation and is rocked in the manner hereinbefore described until it is stopped by the stem of the depressed key, whereas the other setting segment corresponding to the other group of keys remains in its normal position. On the other hand, if a key 80 is depressed in each of the two different groups, i. e., the upper and lower groups, both setting segments 49 and 38 are released and each of said segments is rocked until stopped by the depressed key nearest thereto. When two keys 80 are depressed in one and the same group, either upper or lower, both zero stop pawls 65 and 57 are thrown out as above described to permit both the setting segments 49 and 38 to be moved until stopped by the stems of the two depressed keys.

There are two groups of tens carrying mechanisms provided in the present machine, one group being shiftable to effect the proper transfer for any totalizer selected by the coupling members 15 and the other group being shiftable to effect the transfer for any totalizer selected by the coupling members 25.

The means for shifting the first of the above mentioned groups of tens carrying mechanisms will now be described. The segment 38 (Figs. 3 and 6) meshes with a gear 89, loose on a shaft 88, which gear meshes with another gear 90 secured to a shaft 91. Also secured to the shaft 91 is a drum 92 having a cam groove 92a engaged by a guide roller 93 of a plate 94 shiftably mounted on rods 96 and 97. An angular shaped bail 95 connects the plate 94 with another plate (not shown) to form a shiftable frame for carrying, in a manner to be hereinafter described, the tens carrying mechanism into alignment with whichever totalizers are selected by the members 15. From the foregoing it will be seen that when the segment 38 is rocked clockwise, as previously described, it will, through the gears 89 and 90, rotate the drum 92 clockwise (Fig. 3) an extent commensurate with the depressed totalizer selecting key 80. The drum 92 in turn, through the cam groove 92a and roller 93, shifts the frame comprising the plates 94 (only one of which is shown) and bail 95 a like extent to properly position the tens carrying mechanisms, associated with the members 15, into alignment with the totalizer elements which are engaged by the associated members 15.

The means for shifting the other groups of tens carrying mechanisms, which are associated with the members 25, will now be described. The setting segment 49 (Figs. 4 and 6) meshes with a gear 98, loose on the shaft 88, which gear in turn meshes with another gear 99 freely mounted on the shaft 91 and connected by a sleeve 99a to a beveled gear 153. The gear 153 meshes with a beveled pinion 159 pivoted on a stud 161 secured to the hub of a drum 100. The pinion 159 meshes with a beveled gear 160 rigidly connected to a gear 163 engaging an intermediate gear 164 fast on the shaft 88. Also secured to the shaft 88 is another gear 181 engaging the toothed sector 156 of the totalizer selecting lever 157. Inasmuch as the lever 157 is not operated during adding operations it will, through the means just described, cause the gears 163 and 169 to remain stationary. It will thus be seen from the above that when the setting segment 49 is rocked counter-clockwise, as previously described, during adding operations it will, through gears 98, 99, and 153, rotate the beveled pinion 159. With the beveled gear 160 held stationary, as previously mentioned, the pinion 159 will rotate around said gear in a planetary manner to rotate the drum 100. The drum 100 has formed therein a cam groove 100a engaged by a guide roller 101 of a plate 102 shiftably mounted on the rods 96 and 97. The plate 102 is connected by means of an angular shaped bail 103 to a second plate 102 (not shown) to form a frame shiftably mounted on the rods 96 and 97. This frame carries the tens carrying mechanisms for any totalizers selected by the members 25.

The cam grooves 92a and 100a in the drums 92 and 100, respectively, are shaped the same as the corresponding grooves in the drums 31 and 44 previously described. Inasmuch as the setting 75

segments 34 and 38 are moved simultaneously and like extents, the members 15 and the frame 94-95, carrying the tens carrying mechanisms, will thereby be shifted simultaneously and like extents. Also, since the setting segments 46 and 49 are moved simultaneously and like extents, the members 25 and the frame 102-103, carrying the tens transfer mechanisms, will thereby be shifted simultaneously and like extents. In other words, the frame 94-95 will be shifted in the same direction as the members 15, while the frame 102-103 will be shifted in the same direction as the members 25.

The tens carrying mechanism associated with the members 15 and carried by the shiftable frame 94-95 will now be described. The horizontal shank of the angular bail 95 is provided with a plurality of projections 104 (Figs. 3 and 10), the space between each pair of which forms a recess for each denominational order, to receive an arm 105a connected by a bail 105d to a tens carrying lever 105. The levers 105 are loosely mounted on a rod 106 and are shiftable with the frame 94-95. Each of the levers 105 corresponds to a different denominational order and carries a tens counter-tooth 107. Each tooth 107 is slidably mounted on its respective lever 105 by means of two elongated slots through which project pins 105b carried by the lever. In addition, each tooth 107 is provided with a cam slot concentric with the rod 106 and engaged by a rod 108 carried by the totalizer carriers 16. The tooth 107 of each denominational order and its appropriate member 15 are in one and the same plane. Thus, due to the fact that the sleeve 14 and the frame 94-95 are shifted together and in the same manner, the tooth 107 will always be opposite the adding wheel 10 which is engaged by its respective member 15 to couple said wheel to its setting wheel 12. It will thus be seen that the tooth 107 is shiftable with the lever 105 and, through its mounting on the pins 105b, is also adapted to be shifted by the rod 108 with the totalizer carrier 16 when the latter receives its rocking movement.

Each lever 105 has an extension 105c provided with three notches. These notches cooperate with a rod 110 (Figs. 10 and 7) of a spring-pressed locking bail 111, pivotally mounted on a shaft 112, extending the full width of its respective denominational order. During actuation of an adding wheel 10, when passing from "9" to "0", the long tooth 10a thereon will coat with the upper end of the tooth 107 and rock the lever 105 counter-clockwise, in which position it is held by the rod 110 which moves into the second notch of the extension 105c when the arm 105 moves downwardly. The lever 105 is given an additional counter-clockwise movement by means 60 to be hereinafter described, whereupon the rod 110 enters the third or uppermost notch of the extension 105c and holds the lever 105 in such position. The upper end of the arm 105a on the lever 105 is provided with a cam slot 113 which is engaged by a pin 114 of a toothed sector 115 pivoted on a shaft 116. In rest position, the pin 114 abuts the left-hand end portion of the slot 113, which portion is concentric with the shaft 106. This prevents the sector 115 from being rocked 70 during the first counter-clockwise movement imparted to the lever 105, while during the second counter-clockwise movement given to the lever 105 the sector 115 is rocked counter-clockwise by the lower portion of the slot 113 in the arm 105a.

Each toothed sector 115 is guided by a pair of extensions 117 (Fig. 8) integral with the vertical shank of the bail 95, there being a pair of such extensions associated with each denominational order. Through such guides, the 5 toothed sectors 115 are shifted with the tens carrying levers 105 so that the sectors 115 are always positioned opposite the adding wheel 10 of next higher denominational order from the adding wheel 10 coupled by the member 15 to the setting wheel 12.

The other group of tens carrying mechanisms, which corresponds to the members 25 and is associated with the shiftable frame 102-103, will now be described. Allotted to each denominational order is a tens carrying lever 120 (Fig. 11) which is shaped like, and functions in substantially the same manner as, the tens carrying lever 105 before referred to. Each lever 120 is connected by a bail 120d to an arm 120a which 20 is associated with the next higher denominational order. The levers 105 and 120 are both loosely mounted on the shaft 106 (Fig. 8), in alternate sequence, and are adapted to be operated independently of each other. The arms 120a of the 25 levers 120 are embraced by extensions 122 on the bail 103 formed as part of the shiftable frame 102-103. Whenever the frame 102-103 is shifted laterally in the manner hereinbefore described, the levers 120 will be shifted therewith. 30

Slidably mounted on pins 120b of each lever 120 is a tens counter tooth 121, which is constructed and operates like the tens counter tooth 107 previously described in connection with the lever 105. The rod 108 is straddled by a bifurcated portion 35 of the tooth 121 and serves to guide the tooth in its movements. The tooth 121, like the tooth 107, is always positioned opposite the adding wheel 10, of its respective denominational order, which has been coupled by the member 25 to the setting wheel 12.

Like the levers 105, each lever 120 has an extension 120c provided with three notches. These notches cooperate with a rod 123 of a spring-pressed lock bail 124, pivotally mounted on the 45 shaft 112 (Fig. 7), extending over the full width of its respective denominational order. During actuation of an adding wheel 10, as the latter passes from "9" to "0", the long tooth 10a thereon will coat with the upper end of the tooth 121 and thereby rock the lever 120 counterclockwise, in which position it is held by the rod 123 engaging the second notch of the extension 120c. The lever 120 is given an additional counter-clockwise movement by means to be hereinafter described, 55 whereupon the rod 123 enters the third or uppermost notch of the extension 120c and holds the lever 120 in such position. The upper end of the arm 120a of the lever 120 is provided with a cam slot 125 which is engaged by a pin 126 of a 60 toothed sector 127 pivoted on the shaft 116. In rest position, the pin 126 abuts the left-hand end portion of the slot 125, which portion of the slot is concentric with the shaft 106. This prevents the sector 127 from being rocked during the first 65 counter-clockwise movement imparted to the lever 120, while during the second counter-clockwise movement given to the lever 120, the sector 127 is rocked counter-clockwise by the lower portion of the slot 125 in the arm 120a. 70

Each toothed sector 127 is embraced by projections 128 integral with the bail 103 so as to cause the sectors 127 to take part in the shifting movement which the frame 102-103 receives. In this manner, the sectors 127 are always posi- 75

tioned opposite the adding wheel 10 of the next higher denominational order from the adding wheel 18 coupled by the member 25 to the setting wheel 12.

5 The means for imparting the second counter-clockwise movement, above referred to, to the tens carrying levers 105 and 120 will now be described. Each of the levers 105 and 120 is provided with an extension 105f and 120f, respectively. The extensions 105f and 120f of the two levers 105 and 120 associated with each denominational order cooperate with a tens carrying bail 130 (Figs. 8, 9, 10, 11, and 13), there being one of such bails associated with each denominational order. The bails 130 for the different denominational orders are loosely mounted on a shaft 131, each of said bails being connected to a cam disc 133 by means of a pitman 132 having a guide roller 132a coacting with a cam groove 133a in said disc. The cam discs 133 are secured to a shaft 134 which is given one complete rotation in a counter-clockwise direction at the end of each operation of the machine. The cam grooves 133a in the discs 133 are so shaped that, 15 after the amount differential actuators 13 have been restored to their home positions, they rock the bails 130 first clockwise, then counter-clockwise past their home positions, and finally clockwise to their initial positions. The cam groove 20 133a of the discs 133 are so formed as to actuate the bails in successive order, beginning with the one associated with the lowest denominational order.

30 It will be seen from Figs. 10 and 11 that, if the levers 105 and 120 are not given the initial counter-clockwise movement previously referred to, the bails 130 associated with said levers will pass idly beneath the projections 105f and 120f, respectively, of the levers, without having any effect on the latter. If, however, when an adding wheel 10 passes from "9" to "0", one of the levers 105 or 120 is rocked counter-clockwise into the position shown in Fig. 9 by means of the tens tooth 10a, the projection 105f or 120f thereof is 35 moved directly into the path of its respective bail 130. Thus when the bail 130 is rocked clockwise it will coast with either the projection 105f or 120f, depending upon which has been moved into the path thereof, and rock the lever 105 or lever 50 120 counter-clockwise until it assumes the position shown in Fig. 13. When this occurs, the cam slot 113 of the arm 105a or the cam slot 125 in the arm 120a will cam the pin 114 or 126 and tens carrying sector 115 or 127, respectively, in a 55 counter-clockwise direction.

After the members 15 and 25 and the tens carrying levers 105 and 120 are adjusted laterally into alignment with the selected totalizer, the amount differential actuators 13 are rocked clockwise an extent determined by the amount keys. Just before the actuators 13 are rocked counter-clockwise to their home positions, the totalizer carriers 16 are rocked counter-clockwise to engage the various setting wheels 12 with the actuators 13, so that the latter will, during their counter-clockwise movements, actuate the wheels 12 to add upon the adding wheels 10 of the totalizers selected the amounts which were set up on the actuators 13 under control of the amount keys. 60 After the actuators 13 are thus restored to their home positions, the members 15 and 25 are returned to their normal ineffective positions and the totalizer carriers 16 are rocked clockwise to engage the adding wheels 10 of the selected totalizers with the tens carrying sectors 115 and

127. Thus, if any of the adding wheels 10 passes from "9" to "0", the long teeth 10a thereon will actuate their corresponding tens carrying levers 105 or 120 to adjust the toothed sectors 115 or 127 so that upon rotation of the cam discs 133 the sectors will be actuated thereby in successive order to add "one" upon the adding wheels 10 of next higher denominational order.

Should an adding wheel 10 of next higher denominational order, when having "1" transferred thereto, pass from "9" to "0", the tens tooth 10 thereon will cause one of the projections 105f and 120f on its corresponding tens carrying levers 105 and 120, respectively, to be moved into the path of the appropriate bail 130 shortly before the latter receives its rocking movement. On the clockwise movement of the bail 130 the lever 105 or 120 will be thereby rocked further counter-clockwise and thus cause one of the sectors 115 and 127 associated therewith to be rocked likewise. This 20 causes the sector to add "1" onto the adding wheel 10 of still next higher denominational order. After the proper carry has been effected, the totalizer carriers 16 are rocked counter-clockwise to return the row of totalizers to its normal 25 ineffective position. Also near the end of the cycle of operation of the machine, the cam discs 133 serve to restore the displaced tens carrying mechanisms to their normal positions by first rocking the bails 130 counter-clockwise past their normal 30 positions, at which time the bails 130 strike projections 105g and 120g on the levers 105 and 120, respectively, and rock said levers clockwise to return the toothed sectors 115 and 127 to their normal 35 positions, after which the bails 130 are again rocked clockwise to their normal positions.

Adding operation

A brief description will now be given of the operation of the machine when performing an adding operation wherein a key is depressed in each of the upper and lower groups. The amount is entered upon the amount keys (not shown) and two of the totalizer selecting keys 80 are depressed. Depression of the keys 80 moves the zero stop pawls 57 and 65 out of the path of the two setting segments 38 and 49 (Fig. 1). Upon operation of the machine, the amount differential actuators 13 are moved clockwise an extent commensurate with the value of the depressed amount keys, while the two actuating arms 40 and 144 are rocked clockwise and the two actuating arms 51 and 148 are rocked counter-clockwise (Figs. 1 and 12). Under the tension of their springs 39 and 41, the two setting segments 38 and 49 follow the arms 40 and 144 in the latter's clockwise movement until the face 54 on the segment 38 strikes the lower end of a depressed key 80 and is thereby arrested in its clockwise movement. This causes the pin 36 to abut the lower end of the slot 37 in the segment 38 and thereby arrest the movement of the segment 38 in a position corresponding to that of the segment 39. In a similar manner, the setting segments 49 and 46, under the action of their springs 50 and 52, 60 follow the actuating arms 51 and 148 in the latter's counter-clockwise movement until the face 56 on the segment 49 strikes the lower end of a depressed key 80, thereby arresting the counter-clockwise movement of the segment 49. The setting segment 46, with its pin 47 abutting the upper end of the slot 48 in the segment 49, is also stopped in a position corresponding to that in which the segment 49 is stopped.

Due to the fact that the two setting segments 75

34 and 38 are moved the same extent, as above described, they will, through the medium of the drums 31 and 93, respectively, shift the sleeve 14 and the members 15 thereon (Fig. 7) and the frame 94-95 (Fig. 6) toward the right. This causes the members 15 to couple to the setting wheel 12 the adding wheels of the totalizer selected and aline the tens counter teeth 107 with said adding wheels 10. At the same time, the tens carrying sectors 115 are alined with the corresponding adding wheels 10 of next higher denominational order.

As the two setting segments 46 and 49 are moved counter-clockwise like extents, they will, through the drums 44 and 100, respectively, shift the sleeve 21 and the members 25 thereon (Figs. 5 and 7) and the frame 102, 103 to the left an extent determined by the appropriate key 80 which has been depressed. This causes the members 25 to couple to the setting wheels 12 the adding wheels 10 of the totalizer selected and alines the tens counter teeth 107 with the appropriate adding wheels. At the same time, the tens carrying sectors 127 are alined with the corresponding adding wheels 10 of next higher denominational order.

After thus selecting the two desired totalizers in the manner above described, the totalizer carriers 16 are rocked counter-clockwise sufficient to engage the setting wheels 12 with the amount differential actuators 13 just before the latter begin their counter-clockwise movement to home position. Thus, as the actuators 13 are moved counter-clockwise they will actuate the setting wheels 12 and add upon the adding wheels 10 of the totalizers selected, which have been coupled to the wheel 12 by the members 15 and 25, the amount set up on the actuators 13.

If one of the adding wheels 10, during such adding operation, passes from "9" to "0", the tens tooth 10a thereof will strike the appropriate tens counter tooth 107 and 121 and rock the corresponding tens carrying lever 105 and 120 counter-clockwise (Fig. 9). This positions the projection 105f or 120f, depending upon which one of the levers 105 and 120 is effected, in the path of the tens carrying bail 130 associated therewith. When the actuating arms 144, and 148, (Fig. 6) are restored to their normal positions, the setting segments 34 and 46 (Fig. 3) are thereby also returned to their home positions. This causes, through the drums 31 and 44, the shifting of the sleeves 14 and 21 to their normal ineffective positions so that the members 15 and 25 disengage all adding wheels 10 from the setting wheels 12. Whereupon, the totalizer carriers 16 are rocked clockwise to engage the adding wheels 10 of the two selected totalizers with the tens carrying sectors 115 and 127. The shaft 134 then commences its counter-clockwise rotation and causes the cam discs 133 to first rock each of the bails 130 clockwise, in successive order, beginning with the bail for the lowest denominational order and finishing with the bail for the highest denominational order. During such clockwise movement, the bails 130 will coat with the projections 105f and 120f and rocks the levers 105 and 120, respectively, counter-clockwise. This will cause the arms 105a and 120a, through the slots 113 and 125, respectively, formed therein, to rock the tens carrying sectors 115 and 125 counter-clockwise. The latter, being engaged with the adding wheels of next higher denominational order, will advance said wheels one step of movement. By

rocking the bails 130 clockwise in successive order, beginning with the lowest order and finishing with the highest order, continued tens carrying is provided.

After effecting the transfer of "1" from the wheels of lower order to the wheels of next higher order, the totalizer carriers 16 are rocked counter-clockwise to return the row of totalizers to its normal ineffective position (Fig. 10). During their return movement, the tens carrying bails 130 are rocked by the cam discs 133 first counter-clockwise past their normal positions and then clockwise to their normal positions. The bails 130, during their counter-clockwise movements, coat with the projections 105g and 120g and 15 rock the levers 105 and 120, together with their tens carrying sectors 115 and 127, respectively, clockwise to restore them to their normal positions. At the same time, the actuating arms 40 and 51 (Figs. 3 and 4) are rocked counter-clockwise and clockwise, respectively, to their normal positions and in so doing return the setting segments 38 and 49 to their home positions. Such movement of the segments 38 and 49 causes the frames 94, 95 and 102, 103 to be shifted to their home positions, so that the tens carrying elements 105, 155 and 120, 127 are restored to their initial positions. Finally, the amount keys and totalizer selecting keys 80 are released and returned to their normal undepressed positions by means old and well known in the art.

Total taking operation

When taking a total from any of the totalizers, the totalizer selecting lever 157 (Fig. 14) is used instead of the keys 80 for selecting the proper totalizer. The lever 157 is loosely mounted on the shaft 35, adjacent the bank of keys 80, and has formed integral therewith the toothed segment 156 previously referred to. As already explained, the segment 156 is connected by means of the gears 155c, 155b and 154 (Fig. 5) to the bevelled gear 152, and is, likewise, connected by means of the gears 181, 164 and 163 (Fig. 6) to the bevelled gear 160. Consequently, when the totalizer lever 157 is adjusted to select a particular totalizer, the segment 156 will rotate the two bevelled gears 152 and 160 accordingly. Since the bevelled gears 153 and 158 are held stationary at this time, the gears 152 and 160 will rotate the bevelled pinions 151 and 159 around the stationary gears 153 and 158 in a planetary manner, thereby causing the cam drums 44 and 100 to be rotated accordingly. This causes the sleeve 21 and the members 25 thereon, together with the frame 102, 103 carrying the tens carrying elements 120, 121 and 127, to be shifted to the left, so that the members 25 will couple the adding wheels 10 of the selected totalizer with the setting wheel 12, while the tens counter teeth 121 are positioned opposite the coupled adding wheels. From the foregoing it will be seen that the totalizer selecting lever 157 may be adjusted to cause the members 25 and the associated tens carrying elements to be set for all the adding wheels of any of the totalizers, during which time the members 15 and associated tens carrying elements remain in their normal ineffective positions.

The machine is adapted to perform two kinds of total taking operations, namely, a total or totalizer reset operation and a sub-total or read operation. The time of engagement and disengagement of the setting wheels 12 with the

amount differential actuators 13 governs which one of said kinds of operation the machine performs. For instance, to perform a total taking or totalizer resetting operation, the setting wheels 12 are engaged with the actuators 13 at the very beginning of the latter's clockwise movement. Consequently, the actuator 13 will rotate the setting wheels 12, together with the adding wheels 10 coupled thereto, counter-clockwise until the tens teeth 10a on the adding wheels of the selected totalizer strike the upper ends of the tens carrying teeth 121 and are arrested thereby in their zero positions. The tens carrying teeth 121 are provided with noses 121a, which are so arranged that when the tens teeth 10a strike these noses 121a during reset operations, the levers 120 will not be rocked by the last mentioned teeth. If the setting wheels 12 are disengaged from the actuators 13 before the latter begin their counter-clockwise movement to home position, the adding wheels 10 of the selected totalizers will be left standing in their zero positions. However, if the setting wheels 12 are not disengaged from the actuators 13 before the latter are returned counter-clockwise to their home positions, the amounts originally standing on the adding wheels of the selected totalizer will be added back on said wheels again, as is old and well known in the art.

30 *Transferring a total from one totalizer to another totalizer on the same totalizer line*

Means is also provided for transferring a total from one totalizer to any other desired totalizer 35 on the same totalizer line. A control lever 170 (Fig. 14) is provided for conditioning the machine to perform various kinds of operations, namely, adding operation, total taking or totalizer reset operation, sub-total taking or read operation, and transfer total operation. It is the last mentioned operation which will now be considered.

The control lever 170 has formed integral therewith a segment 171 (Figs. 14 and 15) having a cam groove 171a which is engaged by a guide roller 172 of a bail 173 shiftably mounted on a stud 175 carried by one of the side frames. The bail 173 has formed thereon a forked arm 174 engaging an annular groove formed in the hub of a broad gear 177 shiftably, as well as rotatably, mounted on the shaft 35. Fast to the gear 177 is an angular lever 176. The gear 177 is constantly in mesh with a segment gear 178 secured to the shaft 178a. The shaft 178a and gear 178 are rocked first counter-clockwise and then clockwise during each operation of the machine by the intermittent oscillatory drive mechanism (not shown) hereinbefore referred to. This will cause, through the meshing of the gear 178 with the gear 177, the lever 176 to be rocked first clockwise and then counter-clockwise to its home position during each operation of the machine.

If, however, the lever 170 is set in its "transferring" position, the cam groove 171a causes the bail 173, gear 177 and lever 176 to be shifted toward the left, whereby the lever 176 is moved into the path of the stud 180, while the gear 177 still remains in mesh with the gear segment 178. Thus, when the gear 178 is rocked counter-clockwise, as previously described, it will, through the gear 177, rock the lever 176 clockwise. During such clockwise movement of the lever 176 the end thereof will strike the stud 180 of the totalizer selecting lever, which has been positioned

according to the totalizer selected, and rocks said lever clockwise to restore it to its normal position.

The manner in which the above mentioned mechanism functions to transfer a total from one totalizer to another totalizer on the same totalizer line will now be described.

When preparing the machine for a "transfer" operation, the positioning of the control lever 170 to its "transfer" position causes the lever 176 to be moved into the path of the stud 180 on the totalizer selecting lever 157, as already stated. The latter is positioned to select the totalizer from which it is desired to take a total, whereby, through the gears 155c, 155b, 154, 152, 151 and 153 and the cam drum 44 (Fig. 5) the members 25 are so shifted to the left to couple the adding wheels 10 of said selected totalizer with their associated setting wheels 12. At the same time, the lever 157 (Fig. 6), through the gears 181, 164, 163, 160, 159 and 158 and the cam drum 190, causes the appropriate tens carrying elements 120, 121 and 127 to be shifted to the left accordingly and placed opposite the coupled adding wheels 10.

The totalizer to which the total is to be transferred is selected by depression of one of the totalizer selecting keys 80 (Figs. 1 and 2) in a manner previously described. At the beginning of such "transfer" total operation, the setting wheels 12 (Figs. 10 and 12) are rocked into engagement with the differential actuators 13 as previously described, so that when the latter are rotated clockwise, the adding wheels 10 of the coupled totalizer selected by lever 157 are rotated counter-clockwise until their tens teeth 10a strike their associated tens counter teeth 121, whereby the adding wheels 10 are arrested in their zero position. The actuators 13 are likewise arrested at this point. With the totalizer thus reset to zero and the total taken therefrom now standing on the amount differential actuators 13, the arms 40, 51, 144, 148 and lever 176 are given their regular oscillatory movements. At this time the lever 176 strikes the stud 180 of the totalizer selecting lever 157 and restores the latter clockwise to its home position, whereby also the sleeve 21 and the members 25 thereon, together with the frame 102, 103 with the appropriate tens carrying elements 120, 121, 127, are returned to their normal ineffective positions. Thus the totalizer selected by the totalizer selecting lever 157 for the purpose of taking a total therefrom is now reset to zero and the adding wheels 10 thereof are uncoupled from the setting wheels 12.

If, in this connection, one of the five lower totalizer selecting keys 80 (Fig. 1) has been depressed, the setting segments 38 and 34 (Figs. 1 and 3), being released by the zero stop pawl 57 associated therewith, are able, under the action of their springs 39 and 41, to follow the actuating arms 40 and 144 during their first rocking movement until both of said segments are stopped by the face 54 on the segment 38 striking the stem of the depressed totalizer selecting key 80. Through such setting of the segments 38 and 34, the members 15 and their associated tens carrying elements 105, 107, 115 are shifted accordingly, so that the totalizer determined by the depressed key 80 is selected and coupled to the setting wheels 12.

If, however, one of the four upper totalizer keys 80 (Fig. 2) is depressed, only the zero stop pawl 65 will be thereby thrown out of its effective position. Therefore, during the first rock-

ing movement of the actuating arms 51 and 148 (Fig. 6), the setting segments 49 and 46 (Figs. 2 and 4), under the action of their springs 50 and 52, respectively, follow the movement of the arms 51 and 148 until arrested by the face 56 on the segment 49 striking the stem of the depressed key 80. The arms 51 and 148 (Fig. 6), however, complete their first rocking movement, during which time the lever 176 (Figs. 14 and 15) restores the totalizer selecting lever 157 to its normal position. When this occurs, the differential gears 151 to 153 inclusive, and 158 to 160, inclusive, (Figs. 5 and 6) rotate the drums 44 and 100, respectively, to cause the members 25 and 15 the appropriate tens carrying elements 120, 121 and 127 to be moved out of the positions they assumed under control of the totalizer selecting lever 157 and into new positions determined by the depressed key 80. This causes the coupling 20 and selection of the totalizer to which the total taken from another totalizer is to be transferred.

Now the amount differential actuators 13 are restored to their home positions, with the total standing thereon which was taken from the 25 totalizer selected by the totalizer selecting lever 157, at which time the actuators will transfer such total to the newly coupled totalizer selected by the depressed key 80. If, during such transferring operation, some of the adding 30 wheels 10 of the newly selected totalizer pass from "9" to "0," the proper tens carrying is effected by the appropriate tens carrying levers 105 or 120, said levers being rocked just as in regular adding operations. After the amount 35 has been transferred to the second totalizer, the adding wheels 10 thereof are uncoupled from the setting wheels 12 by means of the members 15 or 25 being returned to their normal ineffective positions and the adding wheels 10 coupled with 40 the appropriate tens carrying sectors 115 or 127 through the rocking of the totalizer carriers 16 clockwise. Rotation of the shaft 134 then causes the proper tens carrying to be completed in denominational order, after which the totalizer row is rocked counter-clockwise to its normal or unengaged position (Fig. 10), while the tens carrying elements are restored to their initial positions.

Modified form of the invention

50 A modified form of the invention hereinbefore described and illustrated is shown in Figs. 16 and 17. This second embodiment of the invention functions in a manner similar to that of the first embodiment to accomplish the same results. In the modified form of the invention there are provided, in place of the members 15 and 25 shiftably mounted in the hubs of the setting wheels 12, coupling wheels 15' and 25' 55 which are shiftably mounted on a common shaft 167 and adapted to couple the adding wheels 10 of the selected totalizers to broad setting wheels 12'. Also in such modified form of the invention the amount differential actuators 13 are constantly in mesh with the broad setting wheels 12', which are rotatably mounted on a shaft 166. The coupling wheels 15' and 25' are in constant mesh with the setting wheels 12' and are carried by frames 14' and 21', respectively. The 60 frames 14' and 21' correspond to the sleeves 14 and 21 in the preferred form of embodiment of the invention, and like said sleeves have secured to the right ends thereof plates substantially like the plates 27 and 42, respectively. The frames 65 14' and 21', together with their coupling wheels

15' and 25', respectively, are shiftable relatively to each other in the same manner as the sleeves 14 and 21 before described. The wheels 15', like the members 15, are shiftable toward the right to select the adding wheels of any one of the totalizers from the ninth down to and including the second totalizer, while the wheels 25', like the members 25, are shiftable to the left to select the adding wheels of any one of the totalizers from the first to and including the ninth totalizer.

10 While the forms of mechanisms herein shown and described are admirably adapted to fulfill the objects primarily stated, it is to be understood that it is not intended to confine the invention to the two forms or embodiments herein disclosed, for it is susceptible of embodiment in various forms all coming within the scope of the claims which follow.

What is claimed is:

1. In a machine of the class described, the 20 combination of a plurality of accumulators arranged adjacent one another on a common shaft; and a plurality of shiftable selecting members associated with each denominational order; and a separate means to shift each selecting member relatively to said accumulators to select one or more of said accumulators to receive entries during an operation of the machine.

2. In a machine of the class described, the 30 combination of a plurality of accumulators arranged adjacent one another on a common shaft; a plurality of adjustable means; and a plurality of groups of shiftable selecting members each being under control of one of said 35 means, said different groups of members being shiftable relatively to one another by said means to different extents commensurate with the adjustment of said means to select one or more of said accumulators to receive entries during 40 an operation of the machine.

3. In a machine of the class described, the combination of a plurality of totalizers comprising adding wheels arranged in interspersed order on a common shaft; a separate setting 45 element associated with each denominational group of said adding wheels; differentially movable actuators for actuating said elements; a plurality of groups of members each group movable relatively to the other group to couple a 50 plurality of adding wheels to each of said elements; and a separate means to move each group of members to simultaneously effect the selection of a plurality of said totalizers for operation.

4. In a machine of the class described, the combination of a plurality of totalizers comprising adding wheels arranged in interspersed order on a common support; a separate setting element associated with each group of said adding wheels of like denominational order; a hub formed integral with each of said elements and having rotatably mounted thereon the adding wheels associated with its respective element; a longitudinal slot formed in each of said hubs; a sleeve associated with each of said elements; a longitudinal slot formed in each of said sleeves; a coupling member carried by each of said sleeves and projecting through the slot in the hub of the element corresponding thereto; another sleeve; a second coupling member associated with each one of the hubs of the elements and projecting through the slot in the hub of its associated element and carried by the latter sleeve and projecting through the slot formed 70 75

in the first mentioned sleeve; notches formed on the inner wall of each of said adding wheels; means for moving said sleeves to variously engage their respective coupling members with the notches of the adding wheels to thereby couple said wheels to their common setting elements in various combinations; and differentially movable actuators for differentially actuating said setting elements and the adding wheels which have been coupled thereto.

5. In a machine of the class described, the combination of a plurality of totalizers arranged in interspersed denominational order on a common support; differential means for actuating said totalizers; a plurality of groups of manipulative devices; a plurality of sets of coupling devices; means connected to each set of coupling devices and settable under control of each group of manipulative devices to adjust the coupling devices to selectively couple the totalizers and the differential means; a special manipulative lever; and means adjusted by the lever when manipulated to supplement the control exercised by one of said groups of manipulative devices over one of said sets of coupling devices to select any of said totalizers for total taking purposes.

6. In a machine of the class described, the combination of a plurality of totalizers arranged in interspersed denominational order on a common support; actuating means for said totalizers; a plurality of groups of members for coupling one or more of the totalizers to the actuating means; a plurality of manipulative devices; means settable under control of the manipulative devices for controlling the positioning of said members to couple the totalizers to the actuating means; a manipulative member; and connections adjusted by the member when manipulated for controlling one of said groups of members to couple one of said totalizers to the actuating means before said groups of members are positioned under control of said manipulative devices to couple one or more of said totalizers with the actuating means.

7. In a machine of the class described, the combination of a plurality of totalizers each consisting of a plurality of denominational elements; differentially movable actuators; a plurality of groups of coupling members each group arranged on a common support and means to shift the coupling members on the support and relatively to the totalizer elements to selectively couple one or more of said totalizers to the actuators at the same time.

8. In a machine of the class described, the combination of a plurality of totalizers each consisting of a plurality of denominational elements; differentially movable actuators therefor; a plurality of coupling members arranged on a common support; means to shift the coupling members on the support and relatively to the totalizer elements to selectively couple one or more of said totalizers to the actuators at the same time; and a plurality of tens transfer mechanisms, one for each of said members, said mechanisms being shifted simultaneously with and the same extent as their corresponding members to properly aline said mechanisms with the totalizer or totalizers coupled to the actuators.

9. In a machine of the class described, the combination of a plurality of totalizers arranged in interspersed denominational order on a common shaft; differentially movable actuators

therefor; a plurality of groups of members, said groups of members being movable relatively to one another to couple a plurality of totalizers to the actuators; and a plurality of groups of tens transfer mechanisms each of said groups being associated with one of said groups of members, said groups of mechanisms being movable relatively to one another to properly aline them with the totalizers coupled to the actuators through the movement imparted to the groups of members.

10. In a machine of the class described, the combination of a plurality of interspersed totalizers arranged on a common shaft; differentially movable actuators therefor; a plurality of groups of coupling members, said groups of members being movable relatively to one another to couple one or more of said totalizers to the actuators for the same operation; and a plurality of groups of tens carrying mechanisms, each group corresponding to one of said groups of members and having mechanisms equal in number to the members in its corresponding group of members, said groups of mechanisms being shiftable in unison with said groups of members to aline the tens carrying mechanisms with the totalizers which are coupled to the actuators.

11. In a machine of the class described, the combination of a plurality of interspersed totalizers on a common shaft; differentially movable actuators therefor; a plurality of groups of coupling members shiftable relatively to the totalizers to select a plurality of totalizers for simultaneous actuation by said actuators; a plurality of groups of tens carrying mechanisms, each group of said mechanisms being associated with one of said groups of coupling members and shiftable in unison therewith; and a plurality of manipulative devices for controlling the simultaneous shifting of all of said groups of coupling members and the groups of tens carrying mechanisms associated therewith to select a plurality of said totalizers and properly aline the tens carrying mechanisms with the totalizers thus selected.

12. In a machine of the class described, the combination of a plurality of totalizers arranged in interspersed denominational order on a common support; differentially movable actuators therefor which are given a subtracting movement and an adding movement during each operation of the machine; a plurality of coupling members shiftable relatively to the totalizers to select any one of the latter for actuation by said actuators; a plurality of tens transfer mechanisms equal in number to said coupling members and shiftable in unison with the latter; manipulative means for shifting said coupling members and tens transfer mechanisms to couple one of said totalizers to the actuators for actuation during the subtracting movement of the latter and properly aline the tens transfer mechanisms with the totalizer thus coupled; and manipulative devices for controlling a further shifting movement imparted to the coupling members and tens transfer mechanisms to couple a different totalizer to the actuators for actuation during the adding movement of the latter for the purpose of transferring the amount standing on the totalizer first coupled with the actuators to the totalizer last coupled with the actuators.

13. In a machine of the class described, the combination of a plurality of interspersed totalizers on a common shaft; differentially movable

- setting members therefor; differentially movable means to rotate the members in two different directions during an operation of the machine; a plurality of groups of coupling members; means to shift one of said groups of coupling members relatively to the totalizers to couple one of said totalizers to the setting members for actuation thereby when the setting members are moved in one direction; and means to shift another group of coupling members relatively to the totalizers to couple another totalizer to the setting members for actuation thereby when the setting members are moved in the other direction.
14. In a machine of the class described, the combination of a plurality of totalizers comprising adding wheels arranged in interspersed order; a plurality of setting elements, each of

said elements carrying all of the adding wheels of a certain denominational order; differentially movable actuators for actuating said elements; a plurality of groups of coupling members, each group of coupling members having a coupling 5 and a non-coupling position, said groups of coupling members being movable relatively to each other; and a plurality of differentially settable means, each one of said plurality of differentially settable means being related to a different group 10 of members and operable to adjust its related group of said members to selectively couple the adding wheels to said setting elements to thereby select a variable number of said totalizers for simultaneous operation. 15

HUBERT NEUREITER.
ALBERT KLAAR.

CERTIFICATE OF CORRECTION.

Patent No. 2,192,164.

February 27, 1940.

HUBERT NEUREITER, ET AL.

It is hereby certified that error appears in the above numbered patent requiring correction as follows: In the heading to the drawings, sheets 1 to 6 inclusive, name of inventor, for "A. NEUREITER ET AL" read H. NEUREITER ET AL; and in the printed specification, page 11, first column, line 51, claim 7, after the word "support" insert a semicolon; and that the said Letters Patent should be read with this correction therein that the same may conform to the record of the case in the Patent Office.

Signed and sealed this 30th day of April, A. D. 1940.

(Seal)

Henry Van Arsdale,
Acting Commissioner of Patents.
